SMOKE GENERATOR

Martin Dwyer, Hewlett Bay Park, N. Y., assignor
to Aerial Products, Inc., Merrick, Long Island,
N. Y., a corporation of Delaware

Application August 28, 1943, Serial No. 500,354

2 Claims. (Cl. 102—65)

1

This invention relates to smoke generators, and more particularly to devices of this character that are adapted to be used for generating smoke screens for landing parties, or as protective coverings for military or naval operations, or to be carried in life rafts, boats or the like, for signaling purposes, especially in an emergency.

Devices of this kind must be of rugged construction, always capable of instant use, and of use in an emergency, and capable of long periods of storage prior to use, without deterioration, or contamination by moisture, irrespective of how severe or wet the environment in which they are kept prior to use. Moreover, devices of this kind should be relatively inert except when intentionally ignited by the user, and, therefore, safe to store and keep without being dangerous fire hazards.

It is an object of this invention to provide devices having characteristics meeting the foregoing requirements.

Another object of this invention is to provide devices of the character described that are completely self-contained and ready for instant use in an emergency without requiring any tools of any kind to put them into use.

Still another object is to provide devices of this kind that are rugged, relatively simple in construction, which have a minimum of working parts and which may be simply and quickly manufactured at comparatively low cost and within a minimum of labor.

To the accomplishment of the foregoing and such other objects as may hereinafter appear, this invention consists in the novel construction and arrangement of parts hereinafter described and then sought to be defined in the appended claims, reference being had to the accompanying drawing forming a part hereof, which shows merely for the purposes of illustrative disclosure, a preferred embodiment of the invention, it being expressly understood, however, that various changes may be made in practice within the scope of the appended claims, without digressing from the inventive idea.

In the drawing in which similar reference characters denote corresponding parts:

Figure 1 is a top plan view of the device;

Figure 2 is a transverse section taken along line 2—2 of Fig. 1 and viewed in the direction of the arrows;

Figure 3 is a transverse section taken along line 3—3 of Fig. 4 and viewed in the direction of the arrows;

Figure 4 is a vertical section taken along line 4—4 of Fig. 1, and also viewed in the direction of the arrows;

Figure 5 is a fragmentary vertical section similar to that of Fig. 4, illustrating the device after

burning of the smoke-producing compound has begun; and

Figure 6 is a fragmentary section illustrating a detail of construction.

5 Referring to the drawing, and first to Fig. 4, 10 denotes a casing, preferably of metal such as galvanized iron or other sheet metal, of any suitable form, and in the present embodiment of cylindrical form. The bottom end of the casing is provided with a tapering portion 11. A bottom cover plate 12 spans the bottom end of the casing or container 10 and is attached to the peripheral edge of the casing or container 10 by suitable means, such as a standard double seam or bead 13, to provide a leakproof or hermetical closure of said bottom end.

An inner lid 14 is fitted within the upper end of the casing or container 10. This lid has cup-like form and is made, preferably, of the same material as the casing 10. A comparatively large opening 15 is provided in the lid. This opening has an upstanding rim 16 which provides a slightly tapering mouth for the opening. A pan-like member 17, preferably of zinc, or other readily combustible metal or material, is suspended from the lid 14 extending into the container through said opening, and being attached to the rim 16 by a crimp seam 18. The member 17 serves as a holder for a priming charge 19 of suitable 20 readily combustible material capable of generating sufficient heat upon being ignited to disintegrate the member 17 and to ignite the smoke-producing compound 20 within the container 10, whose characteristics will be hereinafter described more in detail.

The priming charge 19 is retained within the member 17 by a suitable disc 21 of cardboard, or other readily combustible material, that is fitted into member 17 with a force fit and additionally secured in place by "dope," or other suitable adhesive material (not shown). An additional retaining ring member 22, preferably of the same material as member 17, is also provided to hold the disc 21 in place. This ring is, as shown, also secured suitably to the crimp seam 18.

A suitable igniter, such as a match head 23, preferably of the safety match type, or the like, extends from the priming charge 19 through the disc 21. This igniter, if of the safety type, ignites when a striker surface similar to the striking surfaces of book-type matches, is rubbed across it. When so ignited, it fires the priming compound 19.

55 A cover 25 is fitted into the upper end of the casing 10, being positioned in spaced relationship with the inner lid 14, to provide the space 26 between the two. The cover 25 and the wall of the container 10, as well as the wall of member 14, are all beaded over together at 27 and a

suitable annular gasket 28 (Fig. 2) is interposed between the beaded-over portions of the cover 25 and container 10 to provide a hermetical or leakproof and water-tight seal at the bead 27. Solder, or other means for providing a hermetical seal, at the bead, may be provided.

An opening 29 of comparatively large size is provided in the cover 25. This opening is normally closed and hermetically sealed by a conventional tear strip 30 of well-known construction. A pull ring 31, or any other equivalent means, attached to the tear strip 30, is provided for conveniently removing the latter to expose the contents of the container when the device is to be put into use.

Suitable striker means are provided for igniting the match head 23. To this end, a spring member or clip 32 is suitably secured to the inner side of the cover 25, as by spot-welding or the like, at 33 and 34. A paper or cardboard member 35 provided with a striking surface 35a, similar to striking surfaces on safety match books, is provided. This member 35 has side and end protecting flaps 36, 37 folded over the striking surface 35a, and is inserted between the spring member 32 and the inner surface of said cover member with its striking surface 35a facing the cover member 25. It is removably held in its inserted position by the spring member 32 and extends below the tear strip 30 in the space 26. Removal of the tear strip 30 exposes the striker member 35 and makes it readily accessible to the user. It then may be readily removed from the spring clip 32, and its striking surface 35a exposed by unfolding of the flaps 36, 37. The striking surface 35a may then be rubbed across the match head to ignite the latter, and, in consequence, the priming charge 19. The latter, upon burning, develops sufficient heat to burn away the disc 21, and also to burn away the zinc priming cup or member 17 and to ignite the smoke-producing contents 20 of the container. Once ignited the said contents 20 continue to burn and to produce voluminous clouds of smoke that escape through the openings 15 and 29 to atmosphere, as shown in Fig. 5.

The smoke-producing compound 20 is loaded into container 10 with hydraulic pressure and is of the type that requires a considerable amount of heat to raise it to its kindling temperature, which is higher than that of the priming compound 19; more heat than would be developed by merely striking a match head. For this reason, the priming compound 19 is provided. The latter has a lower kindling temperature than the smoke-producing compound and is easily ignited on ignition of the match head. In burning it develops enough heat to melt the member 17 and to reach the kindling temperature of the smoke-producing compound 20.

Since the match head 23 is preferably of the safety match type, the arrangement herein described results in a smoke-producing device that is very safe to handle, store, and ship, and in which little fire hazard or likelihood of premature combustion exists. The air in space 26, moreover, serves as heat insulation to prevent unwanted ignition of the priming compound 19, should the container be stored in unduly warm places. It is also to be noted, that, until the pan-like member 17 disintegrates due to the burning of the priming charge 19, this priming charge is fully protected and sealed from any contact with the smoke-producing compound 20 or any vapors or gases therefrom.

Moreover, the hermetical sealing of the container as a whole provides a rugged, efficient moisture- and waterproof device capable of withstanding severe and unfavorable atmospheric conditions and environment, and which is self-contained and ready for instant use in an emergency.

The match head could be one of the conventional match heads of the usual striking type. In such event the striking surface 35a need merely be a roughened surface.

It is to be understood, of course, that variation in structural detail within the scope of the claims is contemplated. There is no intention of limitation to the exact details shown and described.

What is claimed is:

- 15 1. In a device of the character described, a container, an inner lid adjacent one end of said container, a cover member spanning said end and lying in spaced relationship with respect to said inner lid, said cover member having an opening, means for attaching said cover member and said inner lid in hermetical sealing relationship with said container, a removable tear strip normally hermetically sealing said opening, said inner lid having an opening, a pan-like member of combustible metal extending downwardly through said last-named opening from the upper side of the inner lid, a rim upstanding from said inner lid about said last-named opening, means to secure said pan-like member to said rim, and a retaining ring of the same material as said pan-like member to hold the contents of the latter in place secured with said member to said upstanding rim.
- 20 2. In a device of the character described, a container for smoke-producing compound or the like, an inner lid of cup-like form fitted within an end of said container, said lid having an opening, an upstanding rim about said opening providing a tapering mouth therefor, a pan-like member of metallic combustible material for a priming charge inserted from the outer side of said lid and extending through said opening, said member being suspended from and secured to said rim, a retaining ring also secured to said rim and serving to retain said priming charge within said pan-like member, a cover fitted into the end of said casing and positioned in spaced relationship to said inner lid, means for joining said cover and said inner lid to said container with an hermetical seal, said cover having an opening, a tear strip hermetically sealing said last-named opening, and means carried within the space between the cover and inner lid for igniting the said priming compound after removal of said tear strip.
- 25 3. In a device of the character described, a container for smoke-producing compound or the like, an inner lid of cup-like form fitted within an end of said container, said lid having an opening, an upstanding rim about said opening providing a tapering mouth therefor, a pan-like member of metallic combustible material for a priming charge inserted from the outer side of said lid and extending through said opening, said member being suspended from and secured to said rim, a retaining ring also secured to said rim and serving to retain said priming charge within said pan-like member, a cover fitted into the end of said casing and positioned in spaced relationship to said inner lid, means for joining said cover and said inner lid to said container with an hermetical seal, said cover having an opening, a tear strip hermetically sealing said last-named opening, and means carried within the space between the cover and inner lid for igniting the said priming compound after removal of said tear strip.
- 30 4. In a device of the character described, a container for smoke-producing compound or the like, an inner lid of cup-like form fitted within an end of said container, said lid having an opening, an upstanding rim about said opening providing a tapering mouth therefor, a pan-like member of metallic combustible material for a priming charge inserted from the outer side of said lid and extending through said opening, said member being suspended from and secured to said rim, a retaining ring also secured to said rim and serving to retain said priming charge within said pan-like member, a cover fitted into the end of said casing and positioned in spaced relationship to said inner lid, means for joining said cover and said inner lid to said container with an hermetical seal, said cover having an opening, a tear strip hermetically sealing said last-named opening, and means carried within the space between the cover and inner lid for igniting the said priming compound after removal of said tear strip.
- 35 5. In a device of the character described, a container for smoke-producing compound or the like, an inner lid of cup-like form fitted within an end of said container, said lid having an opening, an upstanding rim about said opening providing a tapering mouth therefor, a pan-like member of metallic combustible material for a priming charge inserted from the outer side of said lid and extending through said opening, said member being suspended from and secured to said rim, a retaining ring also secured to said rim and serving to retain said priming charge within said pan-like member, a cover fitted into the end of said casing and positioned in spaced relationship to said inner lid, means for joining said cover and said inner lid to said container with an hermetical seal, said cover having an opening, a tear strip hermetically sealing said last-named opening, and means carried within the space between the cover and inner lid for igniting the said priming compound after removal of said tear strip.
- 40 6. In a device of the character described, a container for smoke-producing compound or the like, an inner lid of cup-like form fitted within an end of said container, said lid having an opening, an upstanding rim about said opening providing a tapering mouth therefor, a pan-like member of metallic combustible material for a priming charge inserted from the outer side of said lid and extending through said opening, said member being suspended from and secured to said rim, a retaining ring also secured to said rim and serving to retain said priming charge within said pan-like member, a cover fitted into the end of said casing and positioned in spaced relationship to said inner lid, means for joining said cover and said inner lid to said container with an hermetical seal, said cover having an opening, a tear strip hermetically sealing said last-named opening, and means carried within the space between the cover and inner lid for igniting the said priming compound after removal of said tear strip.
- 45 7. In a device of the character described, a container for smoke-producing compound or the like, an inner lid of cup-like form fitted within an end of said container, said lid having an opening, an upstanding rim about said opening providing a tapering mouth therefor, a pan-like member of metallic combustible material for a priming charge inserted from the outer side of said lid and extending through said opening, said member being suspended from and secured to said rim, a retaining ring also secured to said rim and serving to retain said priming charge within said pan-like member, a cover fitted into the end of said casing and positioned in spaced relationship to said inner lid, means for joining said cover and said inner lid to said container with an hermetical seal, said cover having an opening, a tear strip hermetically sealing said last-named opening, and means carried within the space between the cover and inner lid for igniting the said priming compound after removal of said tear strip.
- 50 8. In a device of the character described, a container for smoke-producing compound or the like, an inner lid of cup-like form fitted within an end of said container, said lid having an opening, an upstanding rim about said opening providing a tapering mouth therefor, a pan-like member of metallic combustible material for a priming charge inserted from the outer side of said lid and extending through said opening, said member being suspended from and secured to said rim, a retaining ring also secured to said rim and serving to retain said priming charge within said pan-like member, a cover fitted into the end of said casing and positioned in spaced relationship to said inner lid, means for joining said cover and said inner lid to said container with an hermetical seal, said cover having an opening, a tear strip hermetically sealing said last-named opening, and means carried within the space between the cover and inner lid for igniting the said priming compound after removal of said tear strip.
- 55 9. In a device of the character described, a container for smoke-producing compound or the like, an inner lid of cup-like form fitted within an end of said container, said lid having an opening, an upstanding rim about said opening providing a tapering mouth therefor, a pan-like member of metallic combustible material for a priming charge inserted from the outer side of said lid and extending through said opening, said member being suspended from and secured to said rim, a retaining ring also secured to said rim and serving to retain said priming charge within said pan-like member, a cover fitted into the end of said casing and positioned in spaced relationship to said inner lid, means for joining said cover and said inner lid to said container with an hermetical seal, said cover having an opening, a tear strip hermetically sealing said last-named opening, and means carried within the space between the cover and inner lid for igniting the said priming compound after removal of said tear strip.
